UNITED STATES PATENT OFFICE.

JOHN SEVILLE POOLE, OF CAMBRIDGE, MASSACHUSETTS, ASSIGNOR OF FORTY-NINE ONE-HUNDREDTHS TO HAROLD E. GARRABRANT, OF CAMBRIDGE, MASSACHUSETTS.

AUXILIARY AIR AND FUEL MIXING DEVICE.

Application filed February 9, 1924. Serial No. 691,842.

To all whom it may concern:

Be it known that I, JOHN S. POOLE, a citizen of the United States, residing at Cambridge, in the county of Middlesex and 5 State of Massachusetts, have invented certain new and useful Improvements in Auxiliary Air and Fuel Mixing Devices; and I do hereby declare the following to be a full, clear, and exact description of the invention, 10 such as will enable others skilled in the art to which it appertains to make and use the same.

This invention relates to internal combustion engines and more particularly to an 15 auxiliary carbureting or secondary air and fuel commingling or mixing device for internal combustion engines.

The principal object of the invention is to provide a device of the character referred to, by which unmixed or imperfectly mixed portions of combustible fuel drawn 20 from the ordinary carburetor, may be temporarily subjected to a further commingling and thorough remixture with fresh air supplied from an auxiliary source, to render the explosive charge increasingly combustible as it is sucked through the intake manifold into the respective combustion chambers of an engine.

Another object is to provide a device of 30 the character described which will decrease fuel consumption and increase the operative efficiency of an engine by effecting a thorough mixture of air and fuel in proper proportion.

A further object is to provide an auxiliary air and fuel mixing device or adjuster which will be automatic in its action and wholly eliminate loss of fuel resulting from 40 the imperfect charges or incomplete mixtures effected by the ordinary carburetor when used alone, and which will substantially reduce or eliminate the objectionable carbon deposits caused by a burning of un- 45 mixed fuel unavoidably drawn from the carburetor into the combustion chambers of the engine along with the explosive charges, especially from carburetors which have been long in use.

Simplicity in design and construction permitting quantity production or manufacture at nominal expense and ready adaptability to connection with the intake manifold of an internal combustion engine, are further

desiderata which have been borne in mind 55 in the production of my improved auxiliary mixing device.

The invention will first be hereinafter more particularly described with reference to the accompanying drawings which are to 60 be taken as a part of this specification and then pointed out in the claim at the end of the description.

In said drawings; Fig. 1 is a diagrammatic side elevation of the intake manifold and 65 carburetor of an internal combustion engine, illustrating the application of my improved auxiliary mixing device thereto, the manifold being broken away and shown partly in section.

Fig. 2 is a longitudinal sectional elevation of the auxiliary air introductory and mixing device embodying my invention; and

Fig. 3 is an end section of the same, taken 75 on the line 3—3 of Fig. 2.

Referring to the drawings in which like reference numerals are used to designate corresponding parts throughout the several views, 4 denotes an ordinary carburetor and 80 5 the intake manifold of an internal combustion engine.

My improved auxiliary air introductory and fuel remixing device is preferably introduced in the manifold intermediate the 85 cylinder head and the carburetor, or above the conventional butterfly valve 6 which is usually provided either in the carburetor or in the manifold for a well known purpose.

My improved mixing device is preferably 90 made from solid brass bar stock and comprises a cylindrical body portion 7 having an axial bore or central annular opening extending longitudinally therethrough and formed with a reduced threaded extension 95 8 on one end, while counter-bored at the opposite end to form an annular recess or chamber 9 the base of which is frusto-conically constricted or tapered to provide a valve seat. The walls of said recess or chamber are also partially threaded to receive the correspondingly threaded end of a nozzle 10 100 10 the discharge end of the latter being slightly tapered and exteriorly threaded for engagement within a correspondingly threaded 105 orifice provided in the intake manifold, through which the nozzle is adapted projectingly to extend, and support the de-

vice as shown. A series of longitudinal air channels or passages 11 are provided through the main body portion 7, at spaced intervals around and parallel to the central 5 or axial opening therethrough, said passages being shown terminating in the valve seat or frusto-conical bottom of the recess 9 therein.

A suction plunger or valve 12 which is 10 preferably formed with an enlarged head spaced circumferentially a slight distance from the annular wall of the recess 9 and adapted normally to press firmly upon the tapering seat formed in the base of the latter, is provided for the purpose of closing 15 the air passages when the engine is idle.

Said plunger or valve is carried by a reciprocable stem 13, which extends outwardly 20 through the central opening in the body portion of the device, its projecting end being encircled by an expansible spring 14 and provided with an extremital abutting shoulder or keyed washer 13^a between which and the extension 8 the spring 14 is tensionally confined. Said spring is preferably 25 formed of finely tempered steel to permit a sensitive action of the plunger or valve thereagainst.

A cap 15 having an air screen 16 secured 30 in its outer open end, is adapted to threaded engagement over the reduced extension 8 of the main body portion to provide a protective enclosure for the projecting valve stem and spring, yet permitting free suction of 35 fresh air through the device when the engine is in operation.

For convenience in attachment or removal, the peripheries of the body portion 7 and the cap 15 may be partially knurled 40 as shown.

The operation of my improved auxiliary air introductory and fuel remixing device is as follows:

When the engine is started, a pulsating 45 suction is set up in the intake manifold, as combustible fuel charges are drawn therethrough from the carburetor to the respective combustion chambers. This suction causes the valve 12 to unseat against the 50 tension of spring 14 and allows air to be drawn through the passages 11, around the valve and out through the nozzle 10 into the manifold, where it will be commingled and mixed with the transient combustible 55 gases imperfectly or incompletely mixed and emitted by the carburetor, thus auxiliarily supplying such gases with the requisite amount of oxygen to effect a complete or refined mixture so that incomplete 60 charges or fuel in liquid state will not be

sucked into the combustion chambers with consequent waste and resulting carbon deposits.

It will be understood that when the engine is in operation, the force of suction 65 created in the intake manifold will cause the valve 12 to open or allow it partially to close, depending upon the degree of suction maintained in said manifold under varying speed conditions or the extent of 70 motor acceleration, so that supplementing quantities of air will be admitted or introduced in said manifold through the device in increased proportion to the increased suction or increased quantities of fuel drawn 75 into the manifold from the carburetor.

By reason of the resistances provided by its peculiar arrangement and construction, the air thus drawn through the device is broken up or emitted therefrom in intermittent puffs rather than in a steady flow, 80 so that the air will more freely commingle and mix with the explosive vapors within the manifold.

The simplicity, value and advantages of 85 my improved auxiliarily air introductory and fuel remixing device will be obvious from the foregoing description and it is thought that further explanation or discussion of its merits are unnecessary.

Having thus described my invention, what I claim as new and desire to secure by Letters Patent of the United States, is.

In combination with the fuel inlet manifold of an internal combustion engine, an auxiliarily air introductory device, comprising a main cylindrical body portion having a central opening extending longitudinally therethrough and formed with a reduced extension on one end and a recess 100 in its opposite end providing a valve chamber; air passages extending through said body portion substantially parallel to the central opening therein and terminating in the bottom of said recess, said passages communicating directly between said chamber and the atmosphere; a reciprocable suction-plunger normally seated within said chamber with its stem extended through said opening and adapted to open and close said air passages according to the operation of the engine; a nozzle in open communication with said valve-chamber, secured to and discharging into said manifold; and an open-ended cap secured upon the reduced extension of said body portion enclosing the extended end of the plunger stem, having an air screen secured in its open end.

In testimony whereof I affix my signature.

JOHN SEVILLE POOLE.
